OPERATION OF GLOW DISCHARGES

Helmut Knüppel, Dortmund-Lottringhausen, Germany, assignor to Dortmund-Hörder Hüttenunion Aktiengesellschaft, Dortmund, Germany

Application May 2, 1957, Serial No. 656,629

Claims priority, application Germany May 4, 1956

12 Claims. (Cl. 315—325)

This invention relates to improvements in apparatus for operating a glow discharge for industrial purposes.

The glow discharge is a well-known form of electric discharge between a pair of electrodes disposed in a partly evacuated tube and connected to a voltage source. For a considerable time, glow discharge tubes have been used extensively for illumination purposes, tubes for such purposes commonly being called glow lamps. Glow discharge tubes also serve as elements in electrical or electronic circuits and, in particular, as voltage regulators or stabilizers. In all such applications, the discharge current is of a relatively small order of magnitude and rarely exceeds values of say 50 milliamperes.

More recently glow discharges have also been found useful in industrial fields, the electro-chemical and thermal properties of this type of discharge playing an important role in such applications. The glow discharge may then either serve as a source of thermal energy, or it may be used for the purpose of initiating or effecting chemical reactions, or of treating the surfaces of metal objects. This invention is only related to glow discharges for applications of the latter kind, as distinguished from glow lamps, stabilizers and related devices. One major difference between the two kinds of utilizing glow discharges just referred to lies in the fact that glow discharges for the said industrial purposes are usually operated at currents of an order of magnitude between 5 and several hundreds of amperes. Also, while in the first mentioned low-power devices the evacuated chamber is usually a glass tube of comparatively small dimensions, industrial applications of the glow discharge require vacuum chambers made of steel, chambers which, with regard to shape and size, are comparable to furnaces.

In utilizing a glow discharge for say the purpose of surface treatment, the object to be treated is placed into a vacuum chamber, hereafter referred to as "the vessel." The vessel includes suitable means for supporting the object, and it is equipped with at least two electrodes to which a voltage may be applied through an external circuit. Sometimes, the vessel itself may form one of the electrodes. After the object has been placed into the vessel, the latter is closed and sealed, so that thereupon it may be evacuated until the internal pressure drops to a value at which a glow discharge may be maintained between the electrodes.

It is necessary for most purposes to treat the object in the atmosphere of a gas different from air. For example, nitriding may be carried out in an atmosphere of ammonia, while a gas suitable for carbonization is methane. In such cases the vessel is connected by one pipe to a vacuum pump and by another pipe to a gas supply, the latter pipe comprising a throttle. While the vessel is being evacuated, some gas from the supply is allowed to enter the vessel across the throttle at low pressure. Continuing the process for a sufficient length of time results in the vessel finally being filled with gas, with only a negligible percentage of air remaining. After

the required gas pressure has been established inside the vessel, a voltage of suitable magnitude is applied to the electrodes so that a glow discharge is ignited between the electrodes.

5 Ignition of the glow discharge may be achieved just by raising the voltage sufficiently above the value which is required for subsequently maintaining the discharge. Sometimes, however, the difference between the voltage value required for ignition and the lower voltage value sufficient for maintaining the discharge is undesirably large. In such cases, an auxiliary electrode may be provided, often referred to as ignition electrode.

For operating the glow discharge, either D.-C. or A.-C. may be used. It was found, however, that D.-C. is preferable to A.-C. in many respects, the reason being that the most effective region within a glow discharge is that usually referred to as cathode drop, which region will at all times lie directly adjacent to the object if D.-C. is used and the object is connected to operate as cathode.

15 The major elements of the external circuit usually comprise a source of electric energy and an impedance, both connected in series with each other and with the vessel. If D.-C. is used, the object is often connected directly or indirectly to the negative terminal of the source, thus becoming the cathode, which is done for the reasons explained above.

25 Glow discharges have the well-known tendency to break down to an arc discharge. Such a breakdown is particularly undesirable in the use of glow discharges for the purpose under discussion, because an arc discharge may have a disturbing or even detrimental effect upon the chemical reactions which the glow discharge is to initiate or to affect, and it usually has a damaging effect upon an article under treatment or upon equipment disposed in the vessel, if the arc is sustained for any appreciable time. To operate a glow discharge does not present any major difficulties if the discharge current is comparatively low, a simple resistor connected in series 30 with the vessel then being a sufficient means to eliminate any danger of such breakdowns occurring. This is because in the lower current range a breakdown of the glow discharge to an arc discharge is impossible if the current is prevented from increasing as far as is required for igniting an arc, the arc discharge current being greater than the glow discharge current in the said range. However, if a glow discharge is operated at a higher current this simple means fails, because in the higher current range an arc discharge may exist at a current equal to or even less than the current required to sustain the glow discharge.

35 The border value separating what has been referred to here as the lower and higher current ranges depends to some extent upon circumstantial conditions, such as the nature of the gas, the gas pressure, the voltage, the configuration of the electrodes etc. However, it is safe to say that a simple series resistor will in all probability fail to operate as a breakdown preventing means if the current exceeds the order of magnitude of one ampere.

40 An arc discharge inside the vessel may be tolerated if the arc is allowed to burn for a short period of time only, the length of this time depending upon the type of treatment but, in any event, rarely exceeding the order of magnitude of one tenth of a second. An arc burning for a limited time is found to do no harm to the object under treatment or other parts or equipment inside the vessel. A limitation of the period of time during which the arc discharge is present may be achieved, for example, by providing in the circuit an automatic breaker which is sensitive to the increase in current occurring 45 when the glow discharge breaks down to an arc discharge.

It is also possible to provide means by which the circuit is closed automatically after the arc has been extinguished due to the action of the breaker. The switching means in the circuit may be of the electromechanical or the electronic type. However, extinction of the arc and re-ignition of the glow discharge may also be effected without any electromechanical or electronic switching action if, for example, a circuit is used as it is described in the co-pending United States application for patent by Fritz Harders, Helmut Knüppel, and Karl Brotzmann, Serial No. 515,426, filed June 14, 1955, now Patent No. 2,853,655, and co-pending United States application for patent by Fritz Harders, Helmut Knüppel, and Karl Brotzmann, Serial No. 634,232, filed January 15, 1957, now Patent No. 2,852,721; which latter application is a continuation in part of the first named application, Serial No. 515,426.

In order to extinguish the arc discharge the voltage across the discharge vessel must be lowered under a value at which an arc discharge can exist. This may be accomplished in various ways, and it may be said that the process of extinguishing the arc does not in itself present any major problems. It is only in combination with the additional requirement of re-establishing the glow discharge that certain difficulties arise.

It is therefore one object of the invention to provide means allowing the operation of a glow discharge of high power without any substantial damage being caused to the article under treatment, or other parts or equipment inside the vessel, or any undesirable or detrimental effect upon other kinds of chemical reactions carried out in the vessel, by a possible breakdown of the glow discharge to an arc discharge.

It is another object of the invention to provide means for automatically extinguishing a possible arc discharge within a limited time after the breakdown of the glow discharge to an arc discharge has occurred, and for automatically re-igniting the glow discharge thereafter.

It is a further object of the invention to accomplish the removal of the discharge and the re-instating of the glow discharge by electronic circuit elements.

Other objects of the invention will become apparent from the following description of various embodiments of the invention, illustrated in the drawings.

In accordance with the invention, extinction of an arc discharge is accomplished by automatically firing a gas discharge in a gas-filled bulb which, for example, may be a gas triode of any one of the types known as ignitron, senditron and thyratron. This triode forms part of a circuit loop also comprising the discharge vessel. Re-ignition of the glow discharge in the said vessel is then accomplished by extinguishing the discharge in the said gas triode, as will be explained in greater detail in what follows.

In the drawings

Fig. 1 is a cross-section of a discharge vessel suitable for surface-treating metal objects and for other purposes,

Fig. 2 is a diagram illustrating the pipe connections and electrical connections made to the vessel shown in Fig. 1,

Fig. 3 is a circuit diagram showing a more general form of circuit embodying the invention.

Fig. 4 is a circuit diagram illustrating an embodiment of the invention in more detail,

Fig. 5 is a circuit diagram illustrating another embodiment of the invention,

Fig. 6 is circuit diagram illustrating a further embodiment of the invention, and

Fig. 7 is a plot vs. the time of the discharge current in and the discharge voltage across a discharge vessel in a system according to the invention.

Referring now to Fig. 1, a vessel suitable for surface-treating a metal object in the presence of a glow discharge may consist of a cylindrical container 10 having a lid 11 which may be fastened to a flange 12 of the container 10

by bolts 13, a gasket 14 serving to seal the interior of the container. The object shown is a hollow cylinder of steel, and it is assumed that the inner surface 16 of this object is to be carbonized or nitrided. The cylinder 15 is supported by means of a bracket comprising a flange 17, a conical portion 18 and a rod 19 to which the cylinder 15 is fixed at 20. The conical portion 18 extends through an opening 21 of conical shape in such a way that there is a narrow gap 22 formed between the two conical surfaces. The flange 17 is held in place by several clamps 23 with bolts 24, only one clamp and bolt being shown, with a pair of gaskets 25 and 26 of insulation material serving as sealing means.

A metal rod 27 is arranged coaxially to and inside the object 15, and is supported by a bracket which extends through the sidewall of the vessel and consists of a metal rod 28 covered by a layer 29 of insulation material. Another bracket of similar configuration and thus comprising a rod 30 and an insulation covering 31 carries a metal pin 32 fixed to its inner end. Sleeves 33 and 34 are provided for sealing.

Two pipes, designated 35 and 36, connected to openings 37 and 38 in the side wall, are provided for evacuating the vessel and filling it with gas, as shown in Fig. 2.

The exhaust pipe connects the vessel with a vacuum pump 39 driven by a motor 40. The supply pipe 36 is connected to a gas bottle 41 filled with whatever gas is to be used in the process. Each pipe is equipped with one valve, 42 and 43, valve 43 also serving as an adjustable throttle to control the pressure at which the gas enters the vessel. The pressure inside the vessel may be read from a pressure gauge 44.

Operation of the system will now be described first with no regard to the possibility of the glow discharge breaking down to an arc discharge. After the lid 11 with the object 15 fixed thereto has been fastened to the cylinder 10, pump 39 is set in operation with valve 42 being open and valve 43 adjusted to exert a certain amount of throttle action. This will cause the pressure inside the vessel to drop below atmospheric pressure, the pressure value finally reached in this way depending upon the adjustment of throttle 43. Also, while the vessel is being evacuated the amount of air contained in it will decrease gradually whereas the percentage of gas will increase. If the pump is held in operation for a sufficient length of time, the percentage of air inside the vessel will have become negligible.

In the phase of operation succeeding this evacuation the pressure inside the vessel must be held within certain limits. In some applications, the margin set by these limits is relatively wide. In such cases, operation of the pump may be discontinued and the valve 42 closed. If the pressure then approaches the upper limit of the permissible pressure range before the process is completed the pump may again be operated with the valve 42 open, to lower the pressure sufficiently.

In cases where the aforesaid margin is relatively narrow the pump may be held in operation until the process to be described now is completed.

Let a D.-C. voltage be connected to suitable terminals 45 and 46 on flange 17 and rod 28 resp. in such a way that the object 15, being conductively connected to flange 17, assumes a negative potential relative to rod 27, the latter being conductively connected to rod 28. If the voltage magnitude is suitably selected, a glow discharge will be ignited between rod 27 and the inner surface 16 of object 15. While this glow discharge is maintained, surface 16 and a layer of material just beneath it undergo certain changes in their structure, and particles of the surrounding atmosphere, or components of such particles, will be incorporated into the object within the said region. In this way, carbonizing, nitriding or other treatment or processes may be accomplished. Two examples will now be given, with numerical values that were found suitable:

Example I

For carbonizing the surface of a body of steel, the vessel is filled with methane at a pressure of about 10 millimeters of mercury. The discharge current is then so adjusted as to give a current density of .005 ampere per square centimeter referred to the surface to be treated, which current density, according to experience, corresponds to a voltage of about 800 volts between cathode and anode. An average treatment yielding a satisfactory product will require about 1 hour.

Example II

For nitriding the surface of a body of steel, the vessel is filled with ammonia at a pressure of about 6 millimeters of mercury. The discharge current is then so adjusted as to give a current density of .002 ampere per square centimeter referred to the surface to be treated, which current density, according to experience, corresponds to a voltage of about 600 volts between cathode and anode. An average treatment yielding a satisfactory product will require about 5 hours.

Although the vessel shown in Fig. 1 is equipped for carrying out surface treatments, it will be obvious that the same type of vessel may be used for example in cases where the glow discharge serves the purpose of influencing, initiating or effecting chemical reactions between components of the gas filling.

Referring now to Figs. 3 to 6, showing several embodiments of the invention in the schematic form of wiring diagrams, it will be seen below that, in order to carry out certain switching operations, I make use of electronic switches or relays of the type in which the circuit to be switched is closed by firing a gas discharge in a gas-filled tube and opened by extinguishing that same discharge. Such tubes are well-known to those skilled in the art, the most common types of such tubes being called thyratron, ignitron and senditron. It will be recalled that the thyratron is a gas triode having a continuously emitting thermionic cathode, an anode and a grid disposed between the cathode and the anode, the discharge being fired by raising the grid potential above a critical value, and being extinguished by lowering the anode potential under another critical value. As distinguished herefrom, the gas triode called ignitron has a mercury pool cathode opposed to an anode, the third electrode consisting of a rod made of semiconducting material and having a tip which is immersed in the mercury pool. The ignitron is fired by letting a current exceeding a predetermined value flow in the rod and into the pool, the rod therefore often being referred to as igniter. The senditron is a tube somewhat similar to the ignitron except for the fact that both the anode and the cathode consist of mercury, and that the third electrode or igniter acts electrostatically, the discharge being fired by applying to the igniter a rather high voltage. As in the thyratron, the discharge is extinguished in both the ignitron and the senditron by lowering the anode potential under some predetermined value. It might be mentioned that the type of discharge in these tubes is that of a mercury vapor arc discharge.

All three types of gas-filled tubes just briefly explained may be overloaded for a limited time; however, the amount of permissible overload is considerably greater in the ignitron and the senditron than in the thyratron. If for a given time the discharge current in a thyratron may be raised to say 6 times normal load, the discharge current in an ignitron may be increased for the same time to between 100 and 1000 times normal current, the senditron then being capable of standing without damage an overload about 3000 times normal load. On the other hand, it is an advantage of the thyratron that firing requires a comparatively low voltage and a small amount of energy.

Detailed information on the properties of gas-filled tubes of the type referred to, as well as on the related circuitry,

may be found in "Industrial Electronic Engineering," by W. L. Davis and H. R. Weed, New York 1953, while the thyratron and ignitron and their circuits are treated extensively in "Applied Electronics," by Members of the Staff of the Department of Electrical Engineering, Massachusetts Institute of Technology, New York 1952.

In the symbolism used in the diagrams showing in Figs. 3 to 6, the thermionically emitting cathode of the thyratron is indicated by a dot, whereas the mercury pool cathode of an ignitron or a senditron is shown as a shaded segment.

Turning now to Fig. 3, a discharge vessel 50, which may be of the type shown in Figs. 1 and 2, having a cathode 51, an anode 52 and an ignition electrode 53, is shown connected to a source 54 of direct-current electric energy whose negative terminal 55 is directly connected to the cathode 51, while a lead 56 connecting the positive terminal 57 to the anode 52 comprises a resistor 58. 59 is an ignitron whose cathode 60 is connected to cathode 51 and whose anode 61 is connected to anode 52 of vessel 50. The ignitor 62 of ignitron 59 is connected to cathode 60 across a D.-C. source 63 and a switch 64 which is normally open. The ignition electrode 53, which may be of the type of the metal pin 32 shown in Fig. 1, is connected to anode 52 across a resistor 65 and a source 66 of electric energy which may either supply D.-C. or medium frequency A.-C. Connected in parallel to resistor 58 is an impedance consisting of a resistor 67 in series with a capacitor 68. A switch 69, normally open, is connected to terminal 55 and to a node 70 between resistor 67 and capacitor 68. Terminal 55 may be assumed to be grounded as indicated at 71.

Fig. 3 is a largely simplified presentation of a system according to the invention, its purpose being to illustrate the basic functioning of the system without regard to details, such details being shown in Figs. 4 to 6, to be explained below.

At normal operation, with a glow discharge present in vessel 50, switches 64 and 69 are open and the ignitron 59 is dead. With no current flowing in resistor 67, the potential of node 70 equals that of terminal 57. Due to the voltage drop across resistor 58 the potential of anodes 52 and 61 is somewhat less than that of terminal 57, the difference equalling the voltage to which capacitor 68 is charged.

Assume now that the glow discharge in vessel 50 breaks down to an arc discharge and that immediately upon this occurrence switch 64 is closed. The current 50 generated by source 63 and flowing in ignitor 62 will then fire the ignitron 59, which establishes a short circuit across vessel 52, causing the immediate extinction of the arc. The term "short circuit" is of course to be understood cum grano salis hereinasmuch as the ignitron 55 when fired naturally has some apparent resistance. More accurately speaking, the ignitron when fired sets the voltage between the electrodes 51 and 52 to its own discharge voltage which, being in the order of 20 volts, is just about one third or one half the voltage at which 60 an arc can exist in the discharge space between electrodes 51 and 53.

The time necessary to fire the ignitron 59 is extremely short. Therefore, switch 64 need not be held closed for any appreciable amount of time. The ignitron 59 is then 65 allowed to conduct for a short time whereupon switch 69 is closed. Closing switch 69 sets the potential of node 70 to ground potential, or zero potential. With the initial charge of capacitor 68 still present, the potential of ignitron anode 61 is less than the potential of node 70 and, upon closing switch 69, instantaneously assumes a value which is negative with respect to terminal 55 and cathode 60. This instantaneous drop of the potential of anode 61 causes extinction of the ignitron. During the subsequent transient the anode potential increases exponentially and approaches the poten-

tial of terminal 57. At zero current the voltage drop in resistor 58 equals zero, anode 52 of vessel 50 thus assuming a potential which exceeds the value necessary to sustain a glow discharge in vessel 50 and, if the resistance of resistor 58 is suitably dimensioned, causes re-ignition of the glow discharge.

The probability that the discharge in vessel 50 upon ignition re-appears in the form of an arc discharge is the greater, the greater the difference between the voltage across the vessel 50 at normal operation and the voltage at which the glow discharge is ignited. Also, a large difference between these voltages requires a correspondingly large resistance of resistor 58, which is undesirable with regard to the energy dissipated in that resistor. It is for these reasons that I often prefer to provide an ignitron electrode such as electrode 53. While such an electrode may simply be connected to the anode across resistor 65, I prefer to place a source such as source 66 in series with resistor 65, this source supplying a voltage sufficient for permanently maintaining a low-current glow discharge between cathode 51 and electrode 53. Resistor 65 limits the energy of this particular discharge sufficiently to prevent it from breaking down to an arc.

It will now be shown in connection with Fig. 4 how automatic firing and extinguishing the ignitron as well as automatic re-ignition of the glow discharge in the vessel may be obtained. Some of the circuit elements shown in Fig. 3 also appear in Fig. 4 and will therefore be described briefly only.

The discharge vessel designated 72 in Fig. 4 has a cathode 73, an anode 74 and an ignition electrode 75, the latter being connected to the anode 74 across a resistor 76 and a source 77. The leads 78, 79 connecting the electrodes 73 and 74 with the terminals 80 and 81 of the main source 82 comprise resistors 83 and 84. An ignitron 85 having an anode 86, a cathode 87 and an igniter 88 is connected in parallel with the vessel 72 as in Fig. 3, except that the lead 89 connecting anode 86 to anode 74 comprises a resistor 90 and may be broken by the contact system 91 of a relay 92, the contacts of that system being held closed by gravity or spring action, not shown, as long as the relay coil 93 is not energized.

In Fig. 4, a thyatron 94 serves as a switch for igniting the ignitron 87. The thyatron cathode 95 is connected to the ignitor 88, while the thyatron anode 96 is connected to terminal 81 of source 82 across resistors 97 and 98, resistor 97 having a rather low resistance and resistor 98 having a rather high resistance. A node 99 between resistors 97 and 98 is connected to ground 100 across a capacitor 101. A simple two-loop network 102, 103 is connected in parallel to resistor 83, the network comprising a capacitor 104, common to both loops 102 and 103, a resistor 105 and a capacitor 106 in loop 102 and a resistor 107 in loop 103, a voltage source 108 providing a D.-C. bias voltage being connected in series with resistor 107. The grid 109 of thyatron 94 is connected across a resistor 110 to the one plate of capacitor 104 which is not grounded.

Coil 93 of relay 92 forms part of the loop 111 of a three-loop network 111, 112, 113. In this network, the common element of loops 111 and 112 is a capacitor 114 while loops 112 and 113 have a resistor 115 in common. Loop 113 also comprises resistor 90, a capacitor 116 and a resistor 117. The purpose of the networks designated 102, 103 and 111, 112, 113 is to provide time delay. The delaying effect of such networks is well-known to those familiar with the theory of linear networks and will therefore not be explained here in detail, full information being available from such textbooks as "Communication Networks" by Ernst A. Guillemin, John Wiley and Sons, New York 1952.

At normal operation, with the constant discharge current of a glow discharge in vessel 72 flowing in resistor 83, both ignitron 87 and thyatron 94 are dead, the bias

voltage of source 108 keeping the potential of grid 109 below the firing potential. If the glow discharge breaks down to an arc discharge, the discharge current and the proportional voltage drop in resistor 83 abruptly increase; the latter initiating a voltage impulse appearing across resistor 107. This impulse increases the potential of grid 109 sufficiently to fire the thyatron 94. However, due to the retarding action of network 102, 103 the impulse is delayed by a time interval depending upon the time constants of the network. Firing of the thyatron 94 causes capacitor 101, charged to a voltage equaling that of source 82, to discharge itself through the thyatron, the discharge current flowing in ignitor 88 and thus firing the ignitron 85. The resistance of resistor 98 is sufficiently high to let the potential of the anode 96 of thyatron 94 drop to a value at which the thyatron is extinguished.

The ignitron when fired short-circuits the vessel 72 and causes extinction of the arc discharge as has been described in connection with Fig. 3. The ignitron discharge current results in a voltage drop across resistor 90 which in turn causes a current to build up in coil 93 of relay 92 at a rate depending upon the time constants of network 111, 112, 113. The contact system 91 of relay 92 then breaks the ignitron current as soon as the current in coil 93 has reached a value sufficient to overcome the gravity or spring force acting against the magnetic force of the relay coil. Hence, the ignitron 85 is extinguished after it has been conducting for a time interval depending upon the magnitudes of the elements comprised in network 111, 30 112, 113, the potential of anode 74 thereupon becoming equal to that of terminal 81 with the result that the glow discharge is re-ignited as has been described in connection with Fig. 3.

It will have been noted that in the system shown in Fig. 4 the voltage across the vessel abruptly jumps to a value lying above the ignition value of the glow discharge at the instant the arc discharge is extinguished. In this respect, the system according to Fig. 4 differs from that shown in Fig. 3 where the same voltage under the same conditions increases exponentially, as has been explained. Tests have shown that the discharge in the vessel upon re-ignition is less inclined to take the form of an arc discharge if the voltage across the vessel is increasing at a finite rate and that, for this reason, systems operating as the system shown in Fig. 3 does are preferable. Such systems may for example be built in accordance with Figs. 5 and 6. The circuitry shown in both Figs. 5 and 6 is similar in many respects to that of the systems already described, and a brief description will therefore suffice as far as such similarity exists.

In Fig. 5, a discharge vessel 118 having a cathode 119 and an anode 120 is connected to the terminals 121 and 122 of a D.-C. source 123 by leads 124 and 125, lead 124 comprising a resistor 126 and lead 125 comprising a resistor 127. The vessel 118 may be equipped with an ignition electrode 128 connected to the anode 120 across a source 129 and a resistor 130. The anode 131 of an ignitron 132 is connected to anode 120. The mercury electrode 128 connected to the anode 120 across a resistor 134 to lead 124 in a node 135 located between terminal 121 and resistor 126. The igniter 136 of ignitron 132 is connected to the thermionic cathode 137 of a thyatron 138 whose anode 139 is connected to terminal 122 across a resistor 140, an inductance 141 and a resistor 142. A node 143, located between resistor 142 and the series connection of resistor 140 with inductance 141, is connected to lead 124 across a capacitor 144. The resistance of resistor 142 is large as compared with that of resistor 140. The potential of the grid 145 of thyatron 138 equals the sum of the voltage of a bias voltage source 146 plus the output voltage of a two-loop network 147, 148, loops 147 and 148 having a capacitor 149 in common. In addition to capacitor 149, loop 147 contains a resistor 150, a capacitor 151 and the resistor 126, while loop 148, in addition to capacitor 149, comprises a re-

sistor 152 connected in series with the bias voltage source 146. Node 153 of loop 148 is connected to grid 145 across a resistor 154.

The mercury pool cathode 155 of a second ignitron 156 is connected to lead 124, while its anode 157 is connected to a node 158 which in turn is connected across a resistor 159 to terminal 122 and is also connected across a capacitor 160 to the anode 131 of ignitron 132. The anode 157 of ignitron 156 is further connected to lead 124 across a resistor 161, an inductance 162 and a capacitor 163. The resistance of resistor 159 is large as compared with that of resistor 161. The igniter 164 of ignitron 156 is connected to the thermionic cathode 165 of a thyratron 166 whose anode 167 is connected to terminal 122 of source 123 across a resistor 168, an inductance 169 and a resistor 170, a node 171 located between resistor 170 and the series connection of resistor 168 with inductance 169 being connected to lead 124 across a capacitor 172. A two-loop network 173, 174 in connection with a bias voltage source 175 furnishes the potential of the grid 176 of thyratron 166, loops 173 and 174 having a capacitor 177 as their common element. In addition to capacitor 177, loop 173 contains a resistor 178, a capacitor 179 and resistor 134, while loop 174, in addition to capacitor 177, contains a resistor 180 in series with the bias voltage source 175. Node 181 of loop 174 is connected to grid 176 across a resistor 182.

Lead 124 and, consequently, terminal 121 may be assumed to be grounded, as indicated at 183.

In normal operation, with a glow discharge being present between the electrodes 119 and 120 in the vessel 118, ignitrons 132 and 156 as well as thyratrons 138 and 166 are dead. Let now the glow discharge break down to an arc discharge with the result of a sudden increase in the discharge current and, consequently, a corresponding increase in the voltage drop across resistor 126. This change in the voltage drop across resistor 126 appears in the form of a delayed voltage pulse across resistor 152, the delay depending upon the time constants of the network 147, 148. The voltage pulse across resistor 152 subtracts from the bias voltage of source 146 and, for a brief interval of time, raises the potential of grid 145 sufficiently to fire thyratron 138. The thyratron 138 while conducting allows capacitor 144 to discharge itself through the igniter 136 and the mercury pool cathode 133 of the ignitron 132, the latter being fired thereby. Thyratron 138, after having delivered the charge of capacitor 144, ceases to conduct, capacitor 144 now being re-charged through resistor 142.

Ignitron 132 when fired causes extinction of the arc discharge in the same way as ignitrons 59 and 85 did with regard to the arc discharges in vessels 50 and 72 in the systems shown in Figs. 3 and 4. At the same time, the current in resistor 134, equalling the ignitron discharge current, causes a voltage pulse to appear across resistor 188 which pulse subtracts from the bias voltage of source 175 and thus raises the potential of grid 176 sufficiently to fire the thyratron 166. Capacitor 172 is now discharged through thyratron 166, igniter 164 and mercury pool cathode 155 of the ignitron 156. The discharge current thus fires the ignitron 156 whereupon the thyratron 166 is automatically extinguished as soon as capacitor 172 is nearly discharged. The latter is then re-charged to its original voltage.

Comparing Figs. 5 and 3 will make it apparent that the thyratron 138 is equivalent to switch 64 and the ignitron 156 is equivalent to switch 69, and that resistor 159, node 158 and capacitor 160 are the equivalents of resistor 67, node 70 and capacitor 68, respectively. Hence, the firing of ignitron 156 causes extinction of the discharge in the ignitron 132 in just the same way as the discharge in ignitron 59 was extinguished by the

closing of switch 69. As soon as the ignitron 132 ceases to conduct the voltage across vessel 118 starts increasing again exponentially until the ignition voltage value of the glow discharge is reached, the glow discharge thus becoming re-ignited, with the voltage across the vessel dropping slightly to the value of normal operation. Ignitron 156, too, is extinguished, as it only conducts as long as capacitor 163 is being discharged, the potential of anode 157 then dropping below a value at which a gas discharge between the anode and the cathode of ignitron 156 is possible.

The inductances 141 and 169 are provided to assist in the extinction of the gas discharges in the thyratrons 138 and 166, and similar provisions will often be found in circuits comprising thyratrons. It should be noted, however, that these inductances, although being of advantage, are not to be considered necessary elements of the circuit.

An operation similar to that just described may also be obtained from a system as shown in Fig. 6. In Fig. 6, the discharge vessel is designated 184, and it is shown equipped with a cathode 185, an anode 186 and an ignition electrode 187, the latter being connected to anode 186 across a resistor 188 and a source 189. The cathode 185 is connected to the negative terminal 190 of a D.-C. source 191 by means of a lead 192, which lead is grounded at 193. The anode 186 is similarly connected to the positive terminal 194 of source 191 by means of a lead 195. Lead 192 comprises a resistor 196, while lead 195 comprises a pair of resistors 197 and 198, as well as an inductance 199. A node 200 located between resistors 197 and 198 is connected to ground across a capacitor 201.

The mercury pool cathode 202 of an ignitron 203 is connected to ground, while its anode 204 is connected to the anode 186 of the vessel 184. The igniter 205 of ignitron 203 is connected to the cathode 206 of a senditron 207, the latter having an anode 208 and an igniter 208a. The anode 208 is connected to terminal 194 across a pair of resistors 209 and 210, a node 221 located between these resistors being connected to ground across a capacitor 212. The resistance of resistor 209 is small as compared with that of resistor 210. Means are provided to apply to the igniter 208a a voltage pulse of high magnitude, these means comprising a transformer 213 whose secondary 214 is on the one hand connected to the igniter 208a and on the other hand to the anode 216 of a thyratron 217, while the primary 215 is connected on the one hand to anode 216 and on the other hand to the positive terminal of a D.-C. source 219 whose negative terminal is grounded, as is the cathode 218 of thyratron 217. The lead 220 connecting elements 215 and 219 comprises a resistor 221 and a node 222, the latter being connected to ground across a capacitor 223. It should be noted that the resistance of resistor 221 is large as compared with the impedance of primary 215.

The potential of the grid 224 of thyratron 217 is a function of the time derivative of the voltage drop across resistor 196, a two-loop network 225, 226 producing a delayed voltage pulse whenever there is a change in the voltage drop across resistor 196. The common element of loops 225 and 226 is a capacitor 227. Loop 225 further contains a resistor 228, a capacitor 229 and the resistor 196, while loop 226, in addition to capacitor 227 contains a resistor 230 in series with a bias voltage source 231. A node 232 of the network is connected to grid 224 across a resistor 223.

In normal operation, the current in resistor 196 is constant and equals the discharge current of the glow discharge in vessel 184. The voltage drop across resistor 230 equals zero. The ignitron 203, the senditron 207 and the thyratron 217 all are dead. If the glow discharge in vessel 184 now breaks down to an arc discharge, the sudden increase in current in resistor 196

and the corresponding change in the voltage drop across this resistor will energize the network 225, 226 with the result that a delayed voltage pulse will appear across resistor 230, which pulse raises the potential of the grid 224 of thyatron 217 and thus fires the latter. Capacitor 223 is now capable of discharging itself through the primary 215 of transformer 213 and thereby induces a voltage in the secondary 214. The number of turns in the secondary 214 is so selected that the voltage across the secondary is sufficient to fire the senditron 207 by 10 raising the potential of the igniter 208a above the firing potential. Senditron 207 when fired causes capacitor 212 to discharge itself through the igniter 205 and the mercury pool cathode 202 of the ignitron 203, thereby firing the latter. Ignitron 203 when fired causes extinction of 15 the arc discharge in vessel 184 in exactly the same way as in the systems shown in Figs. 3 to 5. Meanwhile, both the thyatron 217 and the senditron 207 are extinguished as soon as the capacitors 223 and 212 are nearly discharged and the potentials of anodes 216 and 208 20 have dropped below the values at which gas discharges in these tubes are possible.

The circuit loop comprising capacitor 201, resistor 198, inductance 199 and ignitron 203 is oscillatory due to the presence of capacitance and inductance, the damping ratio of a possible oscillation being under-critical because the resistance of resistor 198 can easily be made relatively small. An oscillation is initiated by the closing of the said loop through ignitron 203 when the latter fires. The voltage across capacitor 201 as well as the 30 loop current now begins to change as they do in a damped oscillation with the result that, when the first half-period is completed, the current in the capacitor changes sign. The gas discharge in the ignitron cannot survive this change and is therefore extinguished after an interval of time has elapsed which is equal to, or, to be exact, slightly less than the half period of the oscillation. During the transient succeeding the extinction of ignitron 203 the capacitor 201 is re-charged, the voltage 40 across this capacitor, equalling approximately the voltage across the vessel 184, now increasing exponentially at the time constant of the circuit loop containing capacitor 201, resistor 197 and source 191. When finally the ignition voltage of the glow discharge is reached the discharge in vessel 184 is reignited, conditions now being 45 what they were prior to the breakdown.

The graph shown in Fig. 7 will give a better idea of the total process of extinguishing the arc in the discharge vessel and re-establishing the glow discharge. It is 50 assumed in Fig. 7 that basically operation is similar to the way the systems shown in Figs. 3, 5 and 6 operate. The curve plotted in full lines represents the voltage across the discharge vessel, while the dotted curve illustrates the discharge current. Both variables are plotted vs. the time. The graph is to be understood qualitatively only.

Assume that normal conditions are present up to an instant designated A in Fig. 7. Hence, from the origin to A the voltage will equal the discharge voltage v_g of the glow discharge, while the current will equal the glow discharge current i_g . Let a breakdown to an arc discharge happen at A. The voltage then drops to v_a , equalling the discharge voltage of the arc, while at the same time the current increases to the rather high value i_a . A time interval t_1 now elapses until, at instant B, the ignitron short-circuits the discharge vessel and thus extinguishes the arc. The current now drops to zero and the voltage becomes equal to the discharge voltage v_{ig} of the gas discharge in the ignitron, which discharge voltage is considerably less than v_a and sufficiently small to prohibit an arc discharge from appearing in the vessel. The ignitron is then allowed to conduct for an interval of time t_2 , this interval ending at C where the ignitron is extinguished. At C the voltage starts increasing approximately exponentially until, at D, after a time interval

val. t_3 has elapsed, it reaches the ignition voltage of the glow discharge and thus causes re-ignition of the discharge in the vessel. Re-igniting the discharge in the vessel closes the circuit path through the vessel with the result that the current again reaches its former value i_g , while at the same time the voltage drops to value v_g .

A plot illustrating the functioning of a system operating similarly to that shown in Fig. 4 would be identical with the plot shown in Fig. 7 with the exception that the instants C and D would coincide and, correspondingly, t_3 would equal zero, as will be clear from the explanation given above in connection with the description of Fig. 4.

Certain recommendations will now be given as to the suitable length of time of the intervals t_1 , t_2 and t_3 . It will be recalled that in the examples of possible embodiments of the invention described above the intervals t_1 and t_2 are functions of networks and thus may be selected within rather wide ranges by suitably dimensioning the network elements, the method to be followed being well-known to those skilled in the art. It will also be clear that, whenever bias voltage sources are made use of, the time delays may also be adjusted within certain limits by suitably selecting the bias voltages. It should be mentioned here, however, that a time delay of suitable magnitude may be obtained by other means, such as for example comprising electronic equipment, passive networks having been selected here only in order to simplify the presentation. I should like to emphasize here that I do not want to limit the scope of my invention to any particular method or means to produce time delay. While I usually prefer to replace the networks 179, 180 and 192, 193, 194 in Fig. 3, the networks 147, 148 and 173, 174 in Fig. 5 and the network 225, 226 in Fig. 6 by suitable electronic means, I often prefer to make use of passive linear network elements and configurations for the purpose of controlling the interval t_2 , as such elements and configurations have been shown in Figs. 5 and 6. Also, the interval of time t_3 , if there is any, is preferably obtained by providing a passage linear network, as in Figs. 5 and 6.

It would seem that the time interval t_1 , elapsing between the breakdown of the glow discharge to an arc discharge and the extinction of the arc, should be made as short as possible. While this is generally true, it will often be found that the probability of the discharge to re-appear in the vessel in the form of an arc discharge, or to break down to an arc shortly after the glow discharge has been re-ignited, is reduced if the arc has been allowed to burn for a limited time. While the upper limit of this time is sometimes as high as 10^{-2} seconds, I prefer to let the arc burn for a time between 10^{-5} and 10^{-3} seconds, 10^{-4} seconds being a good average value which makes sure that the arc does not do any harm inside the vessel even under rather unfavorable conditions.

As to the interval t_2 , this is the time during which the vessel is dead and de-ionization of the discharge space between the electrodes of the vessel may take place. I have found that this interval should preferably lie between 10^{-3} and 10^{-1} seconds, in order to obtain sufficient de-ionization without extending this interval to an amount which would make operation rather poor from an economical point of view.

The interval t_3 may be relatively short. While there are cases in which this time interval may be zero and, consequently, a system according to Fig. 4 may for example be used without any major disadvantage, it will be mostly found preferable to have a t_3 of at least 10^{-4} seconds; and I have found that sometimes values as high as 10^{-2} seconds will give optimum efficiency.

One who is skilled in the art will be able to determine in any given case by applying means of computation and/or empirical methods the values and magnitudes of the circuit elements that will put the three time intervals

within the limits given above. Nevertheless, suitable values will be listed here for a system built in accordance with Fig. 5, which values will ensure that $t_1=10^{-5}$ seconds, $t_2=3.10^{-3}$ seconds and $t_3=10^{-4}$ seconds. These values are the following:

Resistors:

Numerical 126	ohms	10^{-1}	
Numerical 127	do	2	
Numerical 130	do	10^4	
Numerical 134	do	10^{-1}	10
Numerical 140	do	2	
Numerical 142	do	10^3	
Numerical 150	do	10^4	
Numerical 152	do	10^5	
Numerical 154	do	10^4	
Numerical 159	do	10^2	
Numerical 161	ohm	1	
Numerical 168	ohms	2	
Numerical 170	do	10^3	
Numerical 178	do	5.10^4	20
Numerical 180	do	10^5	
Numerical 182	do	10^4	

Capacitors:

Numerical 144	farads	4.10^{-6}	
Numerical 149	do	10^{-9}	25
Numerical 151	do	10^{-7}	
Numerical 168	do	10^{-5}	
Numerical 172	do	4.10^{-6}	
Numerical 177	do	5.10^{-8}	
Numerical 179	do	10^{-6}	30

Inductances:

Numerical 141	henrys	10^{-3}	
Numerical 169	do	10^{-3}	

Bias voltages:

Numerical 146	volts	25	
Numerical 175	do	28	

The bias voltages should be adjustable.

The above values apply in a case where the main source of energy 123 produces a voltage between its terminals of 800 volts and, at normal operation, supplies a glow discharge current of 100 amperes at a discharge voltage between the electrodes of the vessel of 600 volts. When the glow discharge breaks down to an arc discharge, the latter voltage will then drop to 50 volts and the discharge current will climb to 375 amperes.

Similar data will also be given for a system built according to Fig. 6 under the assumption that the glow discharge is to be operated at 500 volts and 50 amperes and that the main source of electric energy produces 800 volts.

Resistors:

Numerical 188	ohms	10^4	
Numerical 196	do	10^{-1}	
Numerical 197	do	6	
Numerical 198	do	2.10^{-1}	
Numerical 209	do	4	
Numerical 210	do	500	
Numerical 221	do	2500	
Numerical 228	do	5.10^4	60
Numerical 230	do	10^5	
Numerical 233	do	5000	

Capacitors:

Numerical 201	farads	10^{-3}	
Numerical 212	do	4.10^{-6}	65
Numerical 223	do	75.10^{-8}	
Numerical 227	do	10^{-3}	
Numerical 229	do	10^{-7}	

Inductance:

Numerical 199	henrys	2.10^{-6}	70

Bias voltage:

Numerical 231	volts	8	

The bias voltage should be adjustable. The transformer 213 should be layed out to produce a voltage between 5

and 10 kilovolts across its secondary 214 in order to fire the senditron 207.

It will have been noted that in the embodiments of the invention described above for the purpose of exemplification the process of extinguishing the arc and subsequently re-igniting the glow discharge is initiated by a change in the electrical conditions present in the circuit, these changes resulting directly or indirectly from the breakdown. With regard to the effect of the breakdown upon the electrical conditions in the circuit the primary effect is the sudden drop in the voltage across the discharge vessel, whereas the resulting increase in discharge current is a secondary effect. It will be obvious to any one skilled in the art that there are many feasible and well-known ways to utilize directly or indirectly either the change in voltage or the change in current for initiating the automatic operation of the system. It is for reasons of simplicity that the systems illustrated in the wiring diagrams shown in Figs. 4 to 6 the change in current is made use of to start the system.

What I claim is:

1. In a system for operating a glow discharge at a discharge current exceeding the order of magnitude of one ampere, in combination, a discharge vessel, means to evacuate said vessel, at least two electrodes inside said vessel, a source of electric energy, an electric circuit connecting said source and said electrodes and capable of supplying to said electrodes a voltage and a current sufficient for operating said glow discharge, a gas discharge relay tube having an anode, a cathode and an igniter, said tube being capable of producing when conducting a voltage between said cathode and said anode which is less than the voltage across said vessel at which an arc discharge can exist in said vessel, a first loop in said circuit and comprising said source, said anode and said cathode, a second loop in said circuit and comprising said vessel, said anode and said cathode, means adapted to automatically fire a gas discharge in said tube and thereby to reduce the voltage across said vessel to a value less than the discharge voltage of an arc discharge whenever said glow discharge in said vessel breaks down to an arc discharge, and automatically operative means adapted to subsequently re-extinguish said gas discharge in said tube and thereby to raise the voltage across said vessel to a value at which a glow discharge is re-ignited in said vessel.

2. A system as claimed in claim 1 in which the gas discharge in said relay tube is a mercury vapor type of discharge.

3. A system as claimed in claim 1, in which said cathode of said tube is of the mercury pool type.

4. A system as claimed in claim 1, in which said tube is an ignitron.

5. In a system for operating a glow discharge at a discharge current exceeding the order of magnitude of one ampere, in combination, a discharge vessel, means to evacuate said vessel, at least two electrodes inside said vessel, a source of electric energy, an electric circuit connecting said source and said electrodes and capable of supplying to said electrodes a voltage and a current sufficient for operating said glow discharge, a gas discharge relay tube having an anode, a cathode and an igniter, said tube being capable of producing when conducting a voltage between said cathode and said anode which is less than the voltage across said vessel at which an arc discharge can exist in said vessel, a first loop in said circuit and comprising said source, said anode and said cathode, a second loop in said circuit and comprising said vessel, said anode and said cathode, means adapted to automatically fire a gas discharge in said tube and thereby to reduce the voltage across said vessel to a value less than the discharge voltage of an arc discharge in said vessel whenever said glow discharge in said vessel breaks down to an arc discharge, automatically operative means adapted to subsequently re-extinguish said gas discharge in said tube and thereby to raise the voltage across said vessel to a value less than the discharge voltage of an arc discharge in said vessel whenever said glow discharge in said vessel breaks down to an arc discharge, automatically operative means adapted to subsequently re-extinguish said gas discharge

in said tube and thereby to raise the voltage across said vessel to a value at which a glow discharge is re-ignited in said vessel, and means adapted to delay said re-extinguishing by a predetermined length of time.

6. A system as claimed in claim 5, in which said predetermined length of time is between the orders of magnitude of 10^{-3} and 10^{-1} seconds.

7. In a system for operating a glow discharge at a discharge current exceeding the order of magnitude of one ampere, in combination, a discharge vessel, means to evacuate said vessel, at least two electrodes inside said vessel, a source of electric energy, an electric circuit connecting said source and said electrodes and capable of supplying to said electrodes a voltage and a current sufficient for operating said glow discharge, a gas discharge relay tube having an anode, a cathode and an igniter, said tube being capable of producing when conducting a voltage between said cathode and said anode which is less than the voltage across said vessel at which an arc discharge can exist in said vessel, a first loop in said circuit and comprising said source, said anode and said cathode, a second loop in said circuit and comprising said vessel, said anode and said cathode, means adapted to automatically fire a gas discharge in said tube and thereby to reduce the voltage across said vessel to a value less than the discharge voltage of an arc discharge in said vessel whenever said glow discharge in said vessel breaks down to an arc discharge, automatically operative means adapted to subsequently re-extinguish said gas discharge in said tube and thereby to raise the voltage across said vessel to a value at which a glow discharge is re-ignited in said vessel, means adapted to delay said re-extinguishing by a predetermined length of time, and means adapted to control the rate at which said voltage across said vessel is raised after said gas discharge is extinguished.

8. A system as claimed in claim 7, in which said rate is such that the interval of time elapsing from the extinguishing of said gas discharge in said tube to the re-igniting of a glow discharge in said vessel is between the orders of magnitude of 10^{-4} and 10^{-2} seconds.

9. In a system for operating a glow discharge at a discharge current exceeding the order of magnitude of one ampere, in combination, a discharge vessel, means to evacuate said vessel, at least two electrodes inside said vessel, a source of electric energy, an electric circuit connecting said source and said electrodes and capable of supplying to said electrodes a voltage and a current sufficient for operating said glow discharge, a gas discharge relay tube having an anode, a cathode and an igniter, said tube being capable of producing when conducting a voltage between said cathode and said anode which is less than the voltage across said vessel at which an arc discharge can exist in said vessel, a first loop in said circuit and comprising said source, said anode and said cathode, a second loop in said circuit and comprising said vessel, said anode and said cathode, means adapted to automatically fire a gas discharge in said tube and thereby to reduce the voltage across said vessel to a value less than the discharge voltage of an arc discharge in said vessel whenever said glow discharge in said vessel breaks down to an arc discharge, means adapted to delay said firing of a gas discharge in said tube by a predetermined length of time, automatically operative means adapted to subsequently re-extinguish said gas discharge in said tube and thereby to raise the voltage across said vessel to a value at which a glow discharge is re-ignited in said vessel, and means adapted to delay said re-extinguishing by a predetermined length of time.

10. A system as claimed in claim 9, in which said predetermined length of time by which said firing of a gas discharge in said tube is delayed is between the orders of magnitude of 10^{-5} and 10^{-3} seconds.

11. In a system for operating a glow discharge at a discharge current exceeding the order of magnitude of one ampere, in combination, a discharge vessel, means to evacuate said vessel, at least two electrodes inside said vessel, a source of electric energy, an electric circuit connecting said source and said electrodes and capable of supplying to said electrodes a voltage and a current sufficient for operating said glow discharge, a gas discharge relay tube having an anode, a cathode and an igniter, said tube being capable of producing when conducting a voltage between said cathode and said anode which is less than the voltage across said vessel at which an arc discharge can exist in said vessel, a first loop in said circuit and comprising said source, said anode and said cathode, a second loop in said circuit and comprising said vessel, said anode and said cathode, means adapted to automatically fire a gas discharge in said tube and thereby to reduce the voltage across said vessel to a value less than the discharge voltage of an arc discharge in said vessel whenever said glow discharge in said vessel breaks down to an arc discharge, means adapted to delay said firing of a gas discharge in said tube by a predetermined length of time, automatically operative means adapted to subsequently re-extinguish said gas discharge in said tube and thereby to raise the voltage across said vessel to a value at which a glow discharge is re-ignited in said vessel, means adapted to delay said re-extinguishing by a predetermined length of time, and means adapted to control the rate at which said voltage across said vessel is raised after said gas discharge is extinguished.

12. In a system for operating a glow discharge at a discharge current exceeding the order of magnitude of one ampere, in combination, a discharge vessel, means to evacuate said vessel, at least two electrodes inside said vessel, a source of electric energy, an electric circuit connecting said source and said electrodes and capable of supplying to said electrodes a voltage and a current sufficient for operating said glow discharge, a gas discharge relay tube having an anode, a cathode and an igniter, said tube being capable of producing when conducting a voltage between said cathode and said anode which is less than the voltage across said vessel at which an arc discharge can exist in said vessel, a first loop in said circuit and comprising said source, said anode and said cathode, a second loop in said circuit and comprising said vessel, said anode and said cathode, means sensitive to a change in the electrical conditions in said circuit resulting from a breakdown of said glow discharge to an arc discharge and adapted to automatically fire a gas discharge in said tube and thereby to reduce the voltage across said vessel to a value less than the discharge voltage of an arc discharge in said vessel whenever said glow discharge in said vessel breaks down to an arc discharge, and automatically operative means adapted to subsequently re-extinguish said gas discharge in said tube and thereby to raise the voltage across said vessel to a value at which a glow discharge is re-ignited in said vessel.
